United States Patent Office

Des. 188,061
Patented May 31, 1960

188,061

CLOCK

Joseph Elby, 1076 S. Norton Ave., Los Angeles, Calif.

Filed Oct. 25, 1957, Ser. No. 48,244

Term of patent 7 years

(Cl. D42—7)

Figure 1 is a perspective view of a clock, showing my new design;

Figure 2 is a front elevational view; and
Figure 3 is a side elevational view.

I claim:

The ornamental design for a clock, substantially as shown.
